BIRD HOUSE

Joseph Albert Wettendorf, 711 E. 35th St.,
Kansas City, Mo.

Filed Aug. 8, 1960, Ser. No. 61,666

Term of patent 14 years

(Cl. D31—2)

Fig. 1.

Fig. 2.

Fig. 3.

Fig. 1 is a front perspective view taken from the bottom of a bird house embodying my new design, the top not shown being substantially plain;

Fig. 2 is a front elevational view thereof, the rear being substantially the same as the front shown; and

Fig. 3 is a right end elevational view thereof, the left end being substantially the same as the right end shown.

I claim:

The ornamental design for a bird house, as shown and described.
